COMBINED RESILIENT HOLDER AND CHOPSTICKS

Larry Y. N. Lee, 326 Bloom Drive,
Monterey Park, Calif. 91754

Filed Mar. 15, 1973, Ser. No. 341,687

Term of patent 14 years

Int. Cl. D7—06

U.S. Cl. D7—105

FIGURE 1

FIGURE 2

FIGURE 3

FIGURE 4

FIG. 1 is a front elevation of a combined resilient holder and chopsticks showing my new design;

FIG. 2 is a side elevation thereof;

FIG. 3 is a top plan view thereof on an enlarged scale; and

FIG. 4 is a bottom plan view of FIG. 3.

I claim:

The ornamental design for a combined resilient holder and chopsticks, substantially as shown.
